UNITED STATES PATENT OFFICE

2,433,020

CATALYTIC ALKYLATION OF AROMATIC HYDROCARBONS BY PARAFFINS

Sam B. Becker, Chicago, Ill., assignor to Standard Oil Company, Chicago, Ill., a corporation of Indiana

Application August 14, 1944, Serial No. 549,449

8 Claims. (Cl. 260—671)

1

This invention relates to a hydrocarbon conversion process and it pertains more particularly to the conversion of an aromatic hydrocarbon, such as benzene, with a paraffin hydrocarbon, such as isooctane, to produce alkyl benzenes, such as tertiary butyl benzene, and high antiknock aviation gasoline blending stocks, said conversion being effected by the use of a catalyst comprising hydrogen fluoride.

It is known that aromatics can be alkylated with olefins by means of such catalysts as aluminum chloride, hydrogen fluoride, aluminum chloride promoted by hydrogen chloride, hydrogen fluoride-boron fluoride mixtures, etc.; an object of my invention is to provide a process which does not require the use of olefins or of halogenated hydrocarbons but which can utilize paraffin hydrocarbons per se, particularly isoparaffins. Aromatics have been alkylated with paraffins with such catalysts as sulfuric acid, phosphoric acid and aluminum chloride-hydrogen chloride catalysts; an object of my invention is to avoid the charging stock degradation and catalyst losses which characterize these prior processes. A further object of my invention is to provide an improved method and means for producing valuable high antiknock gasoline components which are particularly valuable for aviation gasolines. A further object is to provide an improved method and means for producing alkyl benzenes directly from paraffins and aromatics and to avoid the necessity of concentrating or even employing olefins in the process. A further object is to increase the simplicity and efficiency of such a process and to decrease the construction and operating expense thereof. A further object is to provide an improved method and means for minimizing catalyst losses even when hydrocarbon gases are vented from the system. Other objects will be apparent as the detailed description of the invention proceeds.

In practicing my invention I contact an aromatic hydrocarbon such as benzene with an isoparaffin such as isooctane with a catalyst comprising hydrogen fluoride at a temperature in the general vicinity of 400° F. and under a pressure of about 1200 to 1300 pounds per square inch with intimate mixing for a period of time of about 5 hours to produce alkyl benzenes such as tertiary butyl benzene.

Instead of employing benzene as the aromatic hydrocarbon I may employ an alkyl benzene such as toluene, xylenes, etc. or a mixture of such alkyl benzenes or a mixture of benzene with one or more alkyl benzenes. Also, I may employ di-

2

cyclic aromatics such as naphthalene, diphenyl, etc., polycyclic aromatics such as anthracene, and alkyl dicyclic and polycyclic aromatics. Substituted aromatics may be employed provided that the substituting group is not affected by the catalyst under conversion conditions.

The paraffin hydrocarbons are preferably isoparaffins such as isobutane, isopentanes, isoheptanes, isooctanes, etc. or mixtures of 2 or more thereof with each other or with normal paraffins. I have found that normal paraffins per se require much more severe operating conditions than isoparaffins, i. e. the use of considerably higher temperatures and pressure or the use of promoters such as boron fluoride. The charging stock is preferably substantially free from olefins since the presence of olefins tends toward the formation of alkyl fluorides; however, small amounts of olefins may be tolerated.

20 The reaction conditions will depend to a considerable extent upon the particular charging stock and the nature of the desired conversion. In all cases I prefer to employ a relatively large volume of catalyst and the ratio of hydrogen fluoride to hydrocarbon in the reactor may, for example, be within the approximate range of 1:1 or higher although beneficial results may be obtained with catalyst to hydrocarbon ratios within the approximate range of 10:1 to 1:10. 25 The mol ratio of aromatic to paraffin may be within the approximate range of 1:2 to 100:1 or higher, good results having been obtained with a ratio of 2:1 and 1:1. The mol ratio will depend to a considerable extent on the nature of 30 the desired product and an excess of paraffins may be employed for the net production of isoparaffins along with alkyl benzenes.

The temperatures employed will likewise vary throughout a considerable range in accordance 35 with the particular charging stocks employed and the nature of the desired products. Temperatures in the general vicinity of 400° F. are suitable for the alkylation of aromatics with isoparaffins but when normal paraffins are employed 40 temperatures as high as 600 to 700° F. may be necessary unless promoters are used. However, when about 5% boron fluoride is used as a promoter, a normal paraffin such as heptane will effect alkylation of benzene at a temperature of 45 about 330° F. to produce ethyl benzene as the main alkylation product along with considerable amounts of isoparaffins and higher boiling alkyl benzenes. I may employ a hydrogen fluoride catalyst containing between about 2 and 20 50 weight per cent of boron fluoride and may effect

alkylation therewith at a temperature not substantially higher than about 400° F. Instead of boron fluoride I may employ other promoters such as active metal halides, for example aluminum, iron, zinc or zirconium halides. The reaction may also be accelerated by nickel surfaces or the use of activated nickel, i. e., nickel catalyst in the form conventionally employed for effecting hydrogenation. A trace of water may also act as a promoter but the amount of water should preferably be less than 1% and may for example be of the order of .01 to 1%.

Without the use of promoters the temperature of the reaction is usually within the approximate range of about 350 to 700° F., isoparaffins such as isoctane requiring temperatures only within the range of 350 to 450° F. With suitable promoters the temperature may be within the approximate range of 400° down to 200° or even as low as 100° F.

The pressure should be sufficient to maintain substantially liquid phase conversion conditions and will, of course, be dependent upon the temperature employed. Generally speaking, relatively high pressures are necessary, i. e. within the range of about 200 to 2000 pounds per square inch or higher. With benzene, isoctane and hydrogen fluoride at about 400° F. the pressure may be of the order of about 1200 to 1300 pounds per square inch. With heptane, benzene, and hydrogen fluoride containing about 5% boron fluoride the pressure may be of the order of about 1000 pounds per square inch for conversion at about 300° to 330° F.

The contact time or space velocity is likewise dependent to a considerable extent on other conversion conditions and may range from a matter of minutes to a matter of hours. In a batch reactor good conversions have been obtained with contact times of 4 to 5 hours but in a continuous reactor provided with high speed mixers the contact time may be more nearly of the order employed in conventional isoparaffin-olefin reactions. On a space velocity basis in a continuous system I may employ about .2 to 2 volumes of hydrocarbon charging stock per hour per volume of catalyst in the reactor.

In a continuous system most of the catalyst may be recycled from a settler back to the reactor and the hydrogen fluoride recovered from the product and from spent catalyst or complex material may be employed as a scrubbing liquid for preventing losses of boron fluoride promoter with hydrocarbon gases which are vented from the system. By recycling selected fractions of the product I may direct the reaction toward the formation of particular alkyl benzenes, aviation blending stocks, etc. The invention will be more clearly understood from the following detailed description read in conjunction with the accompanying drawing which forms a part of this specification and which is a schematic flow diagram of my improved alkylation system.

An aromatic hydrocarbon such as benzene, an alkyl benzene or a benzene-alkyl benzene-mixture is introduced from source 10 by pump 11 to charge line 12. A paraffin hydrocarbon, preferably an isoparaffin or a mixture of isoparaffins such as isobutane, methyl pentanes, isoctane, etc. or a mixture thereof, is introduced from source 13 by pump 14 to charge line 12. Hydrogen fluoride is introduced to charge line 12 from line 15 and the mixture of catalyst and hydrocarbon charging stock may be introduced through heat exchanger 16 to reactor 17 which in this case

operates at a temperature of about 400° F. and at a pressure of about 1300 pounds per square inch. The heat exchanger 16 may be in line 12 prior to the juncture of line 15 therewith or instead of employing a heat exchanger I may employ a jacketed reactor or any other conventional means of temperature control. The reactor in this case may be provided with a high speed stirrer 18 although it should be understood that instead of a stirrer I may obtain the intimate mixture by the use of circulating pumps either within the reactor itself or outside of the reactor in accordance with conventional practice in isoparaffin-olefin alkylation systems. The mixture of catalyst and hydrocarbons passes from reactor 17 by line 19 to settler 20 which may be operated at substantially reactor temperature and pressure. It should be understood, however, that a cooler may be employed in line 19 in order to facilitate the settling of the hydrogen fluoride catalyst from the hydrocarbon layer in the settler and that the settler may operate at any temperature within the approximate range of 100 to 400° F. The settled catalyst may be withdrawn through line 21 and returned by pump 22 and line 15 to the reactor.

The hydrocarbon stream may be passed through line 23 and pressure reducing valve 24 to hydrogen fluoride stripper 25 which in this case is an azeotropic distillation still provided with a suitable heater or reboiler means 26 at its base. An hydrogen fluoride-butane azeotrope passes overhead through line 27 to cooler-condenser 28 and settler 29. The condensed mixture separates into a lower hydrogen fluoride layer which is withdrawn through line 30 and introduced by pump 31 either through line 32 to line 15 or through lines 33 and 34 to absorber 35. The upper butane layer passes over the weir in the settler and is returned by pump 36 in line 37 to stripper column 25.

The product stream which leaves the base of stripper 25 through line 38 may be passed through a bauxite or other conventional treating system for the decomposition and/or removal of alkyl fluorides but since no olefins are employed in my system the use of such a treating system is usually not necessary. The stream from line 38 passes from debutanizer tower 39 which is provided with a suitable heater or reboiler 40 at its base. The overhead from tower 39 is condensed in cooler 41 and introduced into receiver 42 from which any uncondensed gas may be vented through line 43. A part of the condensate withdrawn from the receiver by pump 44 may be returned by line 45 for reflux in tower 39. The remainder of the condensate may be withdrawn from the system through line 46 or returned by line 47 to reactor charge line 12.

The bottoms from tower 39 are introduced through line 48 to isopentane-neohexane tower 49 which may likewise be provided with a suitable heater or reboiler 50 at its base. The overhead from this tower is condensed in cooler 51 and introduced into receiver 52 from which a part of the condensate is returned by pump 53 through line 54 as reflux the remainder being withdrawn through line 55 as a valuable isopentaneneohexane blending stock for aviation gasoline.

The bottoms from tower 49 are introduced through line 56 to recycle tower 57 which is provided with a suitable heater or reboiler 58 at its base. The overhead from this tower may consist of hydrocarbons boiling within the approxi-

mate range of 140 to 260° F., i. e. it may contain benzene, toluene, methyl pentanes, methyl hexanes, etc. The overhead stream is condensed in cooler 59 and introduced into receiver 60 from which a part of the condensate is returned by pump 61 and line 62 for reflux in tower 57. The net condensate is recycled by line 63 to reactor charge line 12.

The bottoms from tower 57 passes by line 64 to low boiling product tower 65 and the overhead from this tower is condensed in cooler 66 and introduced into receiver 67 from which a part of the condensate is returned by pump 68 and line 69 for reflux in tower 65 while the remainder is withdrawn through line 70 as a product stream. When the conversion conditions are such as to produce substantial amounts of ethyl benzene tower 65 may be so operated as to take overhead a stream consisting chiefly of this hydrocarbon. Alternatively, the overhead from tower 65 may be employed as a blending stock for high knock rating motor or aviation fuel.

The bottoms from tower 65, which is provided with suitable heater or reboiler 71, are introduced through line 72 to high boiling products tower 73, which is provided with heater or reboiler 74. The overhead from this tower is condensed in cooler 75 and introduced into receiver 76, a part of the condensate being returned by pump 77 and line 78 for reflux and the remainder being withdrawn through line 79. If desired a higher boiling heavier product such as tertiary butyl benzene may be withdrawn as a side stream through line 80 or recovered in a separate fractionating tower. Higher boiling components are withdrawn through line 81.

A portion of the settled catalyst may be withdrawn from line 21 through a pressure reducing valve in line 82 to hydrogen fluoride recovery drum 83 which is provided with suitable heating means 84. This drum may operate at substantially atmospheric pressure and at a temperature of about 100 to 150° F. The hydrogen fluoride is taken overhead through cooler-condenser 85 to receiver 86 and the condensate may be passed by pump 87 either through line 88, through line 15 or through lines 89, 33 and 34 to absorber 35. Spent tarry material may be withdrawn from the base of drum 83 through line 90. By the simple means hereinabove described catalyst losses may be reduced to such an extent that they are practically negligible.

When a promoter such as boron fluoride is employed it may be introduced from source 91 by pump 92 to charge inlet line 12. Most of the boron fluoride will remain in the catalyst if high pressures are maintained in settler 20. However when boron fluoride is employed it may be desirable to operate settler 20 at a lower pressure so that boron fluoride may be withdrawn from the top of the settler through line 93 and conveyed to the base of absorber 35 wherein it is countercurrently scrubbed at a pressure of the order of 500 to 1000 pounds or more per square inch with hydrogen fluoride introduced through line 34, any required make-up hydrogen fluoride being introduced from source 94 by pump 95. At such pressures and at substantially condenser-water temperatures the boron fluoride is selectively absorbed in the hydrogen fluoride and any hydrocarbons may be vented from the system through line 96. The hydrogen fluoride from the base of the tower is passed by line 97 and pump 98 to line 12. Any gases which accumulate in settler 20 may be vented through line 99, and if desired

this line will likewise lead to the base of absorber 35. When boron fluoride is employed it may be desirable to introduce the bottoms from drum 83 to a settler for recovering aromatic hydrocarbons and to heat the residual spent catalyst complex material to a temperature of 300 to 350° F. for decomposing the complex and recovering hydrogen fluoride and boron fluoride. The recovered hydrogen fluoride and boron fluoride may be either introduced at the base of absorber 35 or charged to the reactor through line 12.

Results obtainable by the use of my invention are shown by a batch run wherein 4.2 mols of benzene were stirred with 2.1 mols of isoctane (2,2,4-trimethyl pentane) in the presence of 4.5 mols of anhydrous hydrogen fluoride in a stirred bomb reactor at a temperature of approximately 400° F. under a pressure of approximately 1300 pounds per square inch for a contact time of approximately 5 hours. Fractionation of the product in this case showed a yield of 65% of theoretical for tertiary butyl benzene based on the octane charge. The product consisted almost entirely of gas (isobutane), unchanged benzene and isoctane, the tertiary butyl benzene, and a very small amount of high boiling material which did not solidify at room temperature. The absence of dibutyl benzene in the product was unexpected and renders the process advantageous for tertiary butyl benzene production.

With regard to the use of an activator with hydrogen fluoride a run was made wherein 298 parts by weight of heptane, 232 parts by weight of benzene, 373 parts by weight of hydrogen fluoride and 19 parts by weight of boron fluoride were introduced into a bomb and intimately contacted by rapid stirring at a temperature of about 330° F. to a pressure which rose from about 700 to 1070 pounds per square inch during the reaction time of about 50 minutes. Practically no hydrocarbon gases lighter than propane were produced and the complex formed only amounted to about 20 parts by weight. In a similar run employing aluminum chloride and hydrogen chloride the complex formation amounted to about 196 parts by weight—practically ten times the amount of complex produced in the hydrogen fluoride-boron fluoride run. The extremely small amount of complex produced and the facility with which catalyst can be recovered from the complex are important features of the invention.

In this second run with boron fluoride promoted hydrogen fluoride 32 weight percent of "condensables" were produced of which approximately 33% was propane and 67% isobutane with no determinable amount of normal butane in the products. The process thus provides a method for producing isobutane of remarkable purity.

The C₆ and heavier hydrocarbons amounted to about 68 weight percent of the total hydrocarbons charged and the analysis of the C₆ and heavier hydrocarbons on a volume percent basis was as follows:

	Per cent
Isopentane	9.6
Hexanes (chiefly methyl pentanes)	2.5
Heptanes	25.6
Benzene	24.6
Toluene	8.1
Ethyl benzene	13.6
Ethyl toluene	6.5
Diethyl benzene	3.0
Heavier products	6.5

Since the recycled hydrocarbons in the system illustrated in the drawing consist essentially

of aromatics and isoparaffins the normal charging stock may be converted almost quantitatively into particular alkyl benzenes, high knock rating aviation blending stocks, isobutane and heavier hydrocarbons. Alkyl benzenes such as ethyl benzene, isopropyl benzene and butyl benzenes are valuable for the preparation of styrene and styrene derivatives and for many other organic syntheses.

While I have described in considerable detail a specific system for practicing the invention on a continuous basis it should be understood that these examples are illustrative only and not by way of limitation since numerous modifications and alternative conditions will be apparent from the above description to those skilled in the art.

I claim:

1. An alkylation process which comprises contacting an aromatic hydrocarbon and a paraffinic hydrocarbon with a catalyst consisting essentially of hydrogen fluoride and between about 2 per cent and about 20 per cent by weight of boron fluoride at a conversion temperature under a pressure sufficient to maintain substantially liquid phase conversion conditions and with sufficient time of contact to effect the production of an alkyl aromatic hydrocarbon and an isoparaffinic hydrocarbon, and separating an alkyl aromatic hydrocarbon and an isoparaffinic hydrocarbon thus produced.

2. The process of claim 1 wherein the paraffinic hydrocarbon charging stock is an isoparaffin.

3. An alkylation process which comprises contacting an aromatic hydrocarbon and a paraffinic hydrocarbon with a catalyst consisting essentially of hydrogen fluoride and between about 2 per cent and about 20 weight per cent of boron fluoride at an alkylation temperature not substantially higher than about 400° F. under a pressure sufficient to maintain the liquid phase for a period of time sufficient to produce an alkyl aromatic hydrocarbon and an isoparaffinic hydrocarbon, and separating an alkyl aromatic hydrocarbon and an isoparaffinic hydrocarbon thus produced.

4. The process of claim 3 wherein the paraffinic hydrocarbon charging stock is an isoparaffin.

5. The process of claim 3 wherein the alkylation temperature is between about 200° F. and about 400° F.

6. A hydrocarbon conversion process which comprises contacting a mixture of an aromatic hydrocarbon and a paraffinic hydrocarbon with a catalyst consisting essentially of hydrogen fluoride promoted by about 2 to about 20 weight per cent of boron fluoride in a liquid phase conversion zone maintained at a conversion temperature, withdrawing products from said conversion zone to a settling zone, returning a liquid catalyst layer from said settling zone to said conver-

sion zone, separating a gas stream comprising boron fluoride from said products withdrawn from said conversion zone and returning the boron fluoride of said gas stream to said conversion zone, introducing hydrocarbon products from said settling zone into a hydrogen fluoride recovery zone, separating hydrogen fluoride from said hydrocarbon products by azeotropic distillation with a normally gaseous hydrocarbon product in said last-named zone, returning recovered hydrogen fluoride to said conversion zone, and subjecting the hydrocarbon products from which both boron fluoride and hydrogen fluoride have been removed to a fractionating step.

7. The process of claim 6 which includes the further steps of introducing liquid hydrogen fluoride at a low temperature into the top of an absorbing zone, introducing said gas stream comprising boron fluoride separated from said products into the base of said absorbing zone, drawing unabsorbed hydrocarbons from the top of said absorbing zone, and introducing hydrogen fluoride with absorbed boron fluoride from the base of said absorbing zone into said conversion zone.

8. The process of claim 6 wherein the paraffinic hydrocarbon charging stock is an isoparaffin.
